TEXTILE DRAWING MECHANISM

Samuel Rushton Walsh, Valley Falls, and George Edward Repass, Pawtucket, R. I., assignors to H & B American Machine Company, a corporation of Maine

Application April 28, 1941, Serial No. 390,740

18 Claims. (Cl. 19—131)

This invention relates to the drawing mechanism of drawing, twisting or spinning frames for operating on fibrous textile materials, and more particularly to a drawing mechanism of the class in which a short, endless rotatable belt or apron is used under the fibers of a moving strand of roving or sliver to support and transport the fibers in their travel through a drafting zone to a forward pair of drawing rolls from an intermediate pair of drawing rolls immediately preceding them.

It is the general object of the present invention to provide a drawing mechanism of the above type having an extensible belt run for supporting the roving or sliver, and improved means for varying and controlling the length of such belt-run as occasion requires for maintaining a control of the fibers through the drafting zone.

A further object of the invention is to provide elevatable belt-pushing means for applying adjustable pressure to the lower belt-run and for compressing together into varied degrees of closeness the portions of the upper and lower runs of the belt near to its front loop so as to lengthen or shorten the length of the active fiber-engaging portion of the upper belt-run by definite adjusted amounts, and in which said means will be movable about a pivot distal from and outside of the zone of action of said belt-pushing means.

An important feature of the invention relates to the provision of a pivoted guide device for laterally guiding the endless belt which is arranged under the fibers, and means carried by and movable with the guide device acting on the lower run of the belt to push the belt against a roll disposed above the path of travel of the fibers whereby a desired and definite elongation of the length of the upper run of the belt may be obtained by adjustment of the guide device and the associated belt-pushing means thereon into different adjusted positions relative to the belt.

With these and other objects in view, the invention consists of certain novel features of construction, as will be more fully described and particularly pointed out in the appended claims.

In the accompanying drawings:

Fig. 1 is a vertical sectional view of a spinning or drawing frame embodying the present invention;

Fig. 2 is a plan view taken on line 2—2 of Fig. 1 with the top rolls removed;

Fig. 3 is a detailed view, on slightly enlarged scale, of the drawing device of the present invention; and

Fig. 4 is a detail view showing the form of the side plates and pivot-shaft receiving opening of the guide frame shown in Fig. 3.

Referring first to Figs. 1 and 2 of the drawings, the usual roller beam of a spinning frame or of a speeder is shown conventionally at 10, and it has at spaced intervals therealong a plurality of roller stands 12, of which one is shown in the present instance, in which is rotatably mounted the lower front roll 13, with which coacts the usual top roll 14. On the roll stand is adjustably secured the bearing block 15 in which is journaled the lower intermediate roll 16 and the lower back roll 17. A back top roll 18 and an intermediate top roll 19 coact with the lower back roll 17 and the lower intermediate roll 16 respectively. The three lower rolls 13, 16 and 17, are all positively driven at different speeds by the usual gearing mechanism, not shown, each of the rolls at a greater speed than the preceding one in a succession commencing with the back roll and forwardly, whereby the draft on the roving or sliver between successive pairs of rolls is increased. The difference in speed between the back roll 17 and the intermediate roll 16 is small, as the draft on the roving between these rolls is slight, but the difference in speed between the intermediate roll 16 and the front roll 13 is greater, in order to give a large draft to the roving passing between these rolls and their respective coacting top rolls. The top rolls 14, 18 and 19 are all preferably covered with a resilient material, such as leather, cork composition, natural or synthetic rubber, which materials have been employed in the art; or, they can be made of metal provided with a smooth operating surface, if desired.

The lower front and back rolls 13 and 17 are of the usual fluted or grooved construction, while the lower intermediate roll 16 is knurled or suitably roughened and drives the endless belt or apron 21 over which the roving or sliver (not shown) supplied from the back rolls 17 and 18 to the intermediate rolls 16 and 19 is fed from these intermediate rolls to the front rolls 13 and 14.

As illustrated in Figs. 1 and 3, the belt 21 passes between the intermediate rolls 16 and 19, runs forward with its upper belt-run 22 extending under and bent slightly upwardly around the front of the positively driven roll 23 rotatable in the bearing block 15, has its front loop 24 free and slightly in advance of the roll 23 and unguided with no encirclement of any guide member internally positioned within this loop, and then extends downwardly over the top of an adjustable

support-bar 25 and thence rearwardly around the roll 16. The roll 23 mounted above the fibers of the roving or sliver is positively driven in a suitable manner. The fibers are supported upon the upper belt-run 22 of the moving leather belt or apron 21 and controlled by the intermediate control roll 23.

The top rolls 14, 18 and 19 may be weighted and held in place by various weighting systems commonly employed in the art, such as, for example, a saddle and stirrup mechanism which is of a well known construction in the art, and which forms no particular feature of the present invention.

The support-bar 25 is carried by and extends laterally across one end of a guide frame or cradle which is mounted at the other end upon a pivot-shaft 26 and comprises side plate members 27. The pivot-shaft 26 is rotatably supported in bearings 28 in the blocks 15 of a plurality of roller stands 12, or in other words, at intervals of eight to ten spindles of the spinning frame or speeder, as the case may be. The side plates 27 are provided with upper recesses 29 to receive and fit around the reduced portions of the lower intermediate roll 16. The support-bar 25 is rigidly secured to the side members 27 of the guide frame and engages the outer surface of the lower belt-run 30 near to the free front loop 24 and pushes the upper and lower belt-runs 22 and 30 against the roll 23 to produce the desired amount of lengthening or shortening of the upper belt-run 22 relative to the arc of contact with the roll 23, as well as the desired extension or retraction of the front loop 24 with respect to the bite of the front rolls 13 and 14.

The pivot end portions of the side plates 27 are shown provided with openings 31 of partially circular shape which receive and have a tight press-fit upon the correspondingly - shaped mounting portion of the pivot shaft 26 whereby a swinging movement of the side plates 27 either upwardly or downwardly will result upon turning of the pivot-shaft in the proper direction by the lever 33 fixedly secured thereto to raise or to lower the bar 25 the desired extent relative to the lower belt-run 30 and thus vary the relative spacing between the roll 23 and the bar 25 and consequently the relative closeness to which the opposite belt-runs are compressed toward each other by the action of the bar 25 so that the nose of the front loop 24 will be positioned as desired.

Various non-circular or polygonal shapes may be provided for the opening 31 of the side plates and for the cross-sectional shape of the interfitting portion of the pivot shaft whereby a non-rotary mounting of the plates relative to the pivot-shaft 26 will be obtained.

The lever 33 is provided at its upper end with a hub 34 fixedly secured as by a set screw 35 to the pivot-shaft 26, and the lever extends downwardly and rearwardly therefrom and terminates at its lower end in an enlarged head 36 provided with an arcuate slot 37 through which extends the shank of a stud 38 carried by the roller stand 12 for clamping the lever 33 in the different adjusted positions to which the lever is manually adjusted by the handle 40.

Two spaced fingers 41 and 42 are provided suitably secured to the pivot-shaft 26 and these fingers which are of substantially flat shape are inclined upwardly from the pivot shaft and adapted to guide the roving or sliver in its lateral di-

rection as it travels forwardly from the back rolls 17 and 18 to the intermediate rolls 16 and 19.

The present invention is not limited to the foregoing illustrated and described embodiment of a three-roll drafting system as it is to be understood that it may be embodied in any of the draft stages of various other forms of drafting systems employing four and five pairs of rolls without departing from the spirit of the invention. We desire it to be understood that we reserve the privilege of resorting to all the mechanical changes to which the device is susceptible, the invention being defined and limited only by the terms of the appended claims.

We claim:

1. In a drawing mechanism, in combination, a single endless belt or apron to support the roving or the sliver, means acting upon the lower run of the belt or apron, means adapted to laterally guide the belt or apron and arranged for movement into different adjusted positions, the said first-named means being carried by and raised and lowered by appropriate movement of said guide means into any of its adjusted positions, and a roll disposed above the line of travel of the roving or the sliver against which the belt or apron is pressed by the action of the said first-named means in any of its adjusted positions.
2. In a drawing mechanism, in combination, a single endless apron or belt to support the roving or the sliver, a guide device for laterally guiding the belt or apron, said guide device being movable in a direction toward and from the sliver, means carried by said guide device movable bodily with the same acting on the outer side of the lower run of the apron or belt to push said belt upwardly, and means distal from said belt-pushing means operably connected to said guide device for moving it so as to adjust the position of said means in different adjusted positions.
3. In a drawing mechanism, in combination, a single endless apron or belt having an upper run to support the roving or the sliver, a guide frame having spaced side members for laterally guiding the edges of the belt or apron and to be movable in a direction toward and from the roving or the sliver, means carried by and movable with said frame acting upon the outer side of the lower run of the apron or belt to push the same upwardly, and means supporting the frame at one end arranged for adjusting said frame and said belt-pushing means to adjust said upper belt-run to a desired length, said support means comprising an element of a geometric shape such that it be non-rotatable with respect to the side members that are mounted thereon.
4. In a drawing mechanism, in combination, a single endless belt or apron to support the roving or the sliver, a roll disposed above the line of travel of the roving or the sliver against which the belt or apron is to be pressed, a bar below the line of travel of the roving or sliver extending transversely of and acting upon the lower run of the belt or apron for pushing it against said roll, and spaced side members disposed at opposite side edges of the belt or apron to laterally guide the same, said side members being connected together at one end by said bar and pivoted for swinging movement in unison into different vertically adjusted positions so as to vary the relative spacing between said bar and said roll and to correspondingly regulate the distance between the upper and lower belt-runs whereby various desired extended lengths of the upper belt-run will be obtainable.

5. In a drawing mechanism, in combination, a single endless belt or apron to support the roving or the sliver, a roll disposed above the line of travel of the roving or the sliver against which the belt or apron is to be pressed, a bar below the line of travel of the roving or sliver extending transversely of and acting upon the lower run of the belt or apron for pushing it against said roll, and spaced side members disposed at opposite side edges of the belt or apron to laterally guide the same, said side members being connected together at one end by said bar and pivoted at their other end for swinging movement in unison into different vertically adjusted positions so as to vary the relative spacing between said bar and said roll and to correspondingly regulate the distance between the upper and lower belt-runs whereby various desired extended lengths of the upper belt-run will be obtainable.

6. In a drawing mechanism, in combination, a single endless belt or apron to support the roving or the sliver, a roll disposed above the line of travel of the roving or the sliver against which the belt or apron is to be pressed, a bar below the line of travel of the roving or sliver extending transversely of and acting upon the lower run of the belt or apron for pushing it against said roll, and spaced side members disposed at opposite side edges of the belt or apron to laterally guide the same, said side members being connected together at one end by said bar, the other end of said side members being provided with a non-circular opening, a rotatable member supporting said side members for swinging movement in unison provided with a non-circular portion of corresponding shape as the said openings in the side members and received by and tightly fitting the same, and means for turning said rotatable member to move said side members and said bar into a desired position to adjust the operating part of the belt or apron to a desired length.

7. In a drawing mechanism, in combination, a single endless belt or apron to support the roving or the sliver, a roll disposed above the line of travel of the roving or the sliver against which the belt or apron is to be pressed, a bar below the line of travel of the roving or sliver extending transversely of and acting upon the lower run of the belt or apron for pushing it against said roll, and spaced side members disposed at opposite side edges of the belt or apron to laterally guide the same, said side members being connected together at one end by said bar, the other end of said side members being provided with a non-circular opening, a rotatable member supporting said side members for swinging movement in unison provided with a non-circular portion of corresponding shape as the said openings in the side members and received by and tightly fitting the same, an arm affixed to said rotatable member for manually turning the same to effect movement of said side members and said bar into a desired adjusted position to obtain a desired length of the upper belt run, and means for securing said arm in its various adjusted positions.

8. In a drawing mechanism, the combination of positively driven bottom draft rolls of successively greater surface velocity, top rolls coating with said bottom rolls, an endless belt or apron on a positively driven bottom roll of less velocity for conducting the roving or sliver to a pair of top and bottom rolls of higher velocity, a movable member acting on the outer side of the lower run of the belt or apron, a positively-driven small roll

disposed above said member and positioned above the line of travel of the belt or apron, and pivotal means supporting said member and adapted to move it into different elevated positions to push said belt or apron against said small roll, said means comprising a guide frame having spaced side members between which said belt or apron moves and swingable relative to said belt to raise said member into various adjusted positions to lift the belt a desired and varied extent and push it against the small roll.

9. In a drawing mechanism, in combination, a positively driven roll, an endless belt on said roll having an upper belt-run arranged for conducting the roving or sliver to the drawing rolls, a positively driven small roll disposed above the line of travel of the roving or sliver and positioned in cooperating relationship with the forward portion of the upper run of said belt, a member beneath said small roll acting against the outer side of the lower run of the belt to support the forward portion thereof, the front loop part of said belt extending through the gap between said member and said small roll and being guided solely thereby, and two spaced pivoted arms forming a pivoted support on which said member for engaging the lower run of the belt is mounted, said member being movable bodily toward and from said small roll by appropriate pivotal movement of said pivoted support so as to vary the gap between said member and said small roll and control the relative spacing between said forward portions of the upper and lower belt-runs whereby the effective working length of the upper belt-run is adjusted and controlled.

10. In a drawing mechanism for textile slivers or rovings, the combination of positively driven bottom draft rolls of successively greater surface velocity, top rolls coating with said bottom rolls, an endless belt or apron on a positively driven bottom roll of less velocity for conducting the roving or sliver to a pair of cooperating top and bottom draft rolls of higher velocity, a member to be raised and lowered acting on the outer side of the lower run of the belt or apron, a small roll disposed above said member and positioned above the line of travel of the belt or apron, and a pivoted frame having spaced arms connected at their outer ends by said member and adapted to move it bodily into different elevated positions to push said belt or apron against said small roll, the pivot for said frame being distal from said belt-pushing member and outside of the zone of action thereof.

11. In a drawing mechanism for textile rovings or slivers, two sets of upper and lower drawing rolls, a plurality of endless belts or aprons on the lower roll of the set forming the feed rolls for the other set of drawing rolls, said belts or aprons each having an upper part extending between the associated lower roll and its companion upper roll and thence running forwardly toward the other set of drawing rolls for conducting the roving or sliver thereto, a roll of smaller diameter than any of said drawing rolls positioned intermediate thereof above the line of travel of the moving roving or sliver from said feed rolls to said forward drawing rolls, said small roll being of such length as to extend laterally over the forward part of all the upper run portions of said belts or aprons, a plurality of members intermediate said drawing rolls beneath said small roll each member acting on the outer side of the lower run of a belt or apron to push the same upwardly, pairs of spaced pivoted arms forming

a frame for laterally guiding the belts or aprons and swingable in vertical planes, each pair of arms being connected at their outer end portions by one of said belt-pushing members, a single pivot shaft upon which all of said arms are mounted for simultaneous swinging movement when said shaft is actuated, and a single control element for the said pivot shaft whereby all of said arms will be actuated in unison and cause all of said belt-pushing members to operate simultaneously on the lower runs of the belts or aprons so as to vary the distance apart between the said small roll and the said belt-pushing members and to adjust the forward part of the upper run of each of said belts to a desired length.

12. The combination with a cradle for long draft spinning frames and an actuating member for the cradle having a portion of geometric shape, the cradle comprising two spaced side plates united at the front part by a cross-bar which serves as a guide over which slides an endless belt, each side plate having its top edge portion formed with a notch to receive a roll for actuating the endless belt, and means in each side plate distal from said cross-bar having a geometric shape corresponding to that of the said portion of the actuating member whereby rotation of said actuating member provides adjustment of the cradle.

13. The combination with a cradle for long draft spinning frames and an actuating member for the cradle having a portion of geometric shape, the cradle comprising two spaced side plates rigidly connected at the front part by a cross-member which serves as a guide over which slides an endless belt, each side plate having its top edge portion formed with a deep notch to receive a bottom roll for actuating the endless belt, and means at the rear part of each side plate having a geometric shape corresponding to that of the said portion of the actuating member whereby rotation of said actuating member provides adjustment of the cradle.

14. In a textile drawing mechanism, the combination with an endless belt actuated by a positively-driven roll, and an element coacting with the upper run of said belt for engaging the roving and conducting it to the drawing rolls of the mechanism, of two plates to be moved one at each side of the belt for laterally guiding said belt, said plates being formed with notch portions for receiving the driving roll of the belt, a cross-member that rigidly unites said plates and maintains them separated at a distance corresponding to the width of the belt, said cross-member engaging the lower run of the belt, and support means for said plates pivotally arranged for actuating the plates and the cross-member in unison to move them so as to position and hold the cross-member and the element coacting with the upper belt-run the desired distance apart for forcing the belt against the said coacting element with the necessary pressure to adjust the effective operating length of the upper belt-run.

15. In a textile drawing mechanism, the combination with a lower endless belt having a free front loop and actuated by a positively-driven roll within the rear loop of said belt, and an element coacting with the upper run of the belt for engaging the roving and conducting it to the drawing rolls, of two movable plates one at each side of the belt for laterally guiding said belt, said plates being formed with notch portions for receiving the driving roll of the belt, a cross-member that rigidly connects the forward parts of

said plates and maintains them separated at a distance corresponding to the width of the belt, said cross-member being disposed beneath the roving-engaging element that coacts with the upper belt-run and engaging the outer face of the lower run of the belt, and support means for said plates connecting together the tail parts of the plates, said means being pivotally arranged for actuating said plates and said cross-member to swing them into vertically adjusted positions and maintain said cross-member and the coacting element for the upper belt-run separated at the required distance apart for forcing the belt against its coacting element with the necessary pressure to adjust the effective operating length of the upper belt-run to the desired extent.

16. In a textile drawing mechanism, the combination of positively-driven lower rolls, top rolls coacting with said lower rolls, an endless traveling belt on a lower roll for conducting the roving to a forward pair of top and lower rolls, the front loop of said belt being free and capable of elongation when squeezed from opposite sides, a movable cross-member engaging the outer face of the lower run of the belt, a positively-driven small roll disposed above said cross-member and coacting with the upper run of the belt, and pivotal means for guiding said belt, said means including said cross-member and comprising a frame having two spaced side plates arranged for laterally guiding the belt and swingable relative thereto to adjust said cross-member into its various elevated positions for positioning the cross-member and said small roll the required distance apart and forcing the belt with the necessary pressure against the small roll to squeeze together the opposite run portions of the front loop of said belt whereby said front loop will be elongated and adjusted to the desired extent relative to the nip of the drawing rolls receiving the roving from said belt.

17. In a textile drawing mechanism, the combination of positively-driven bottom draft rolls of successively greater surface velocity, top rolls coacting with said bottom rolls, an endless belt having its rear loop about and in operative relation with a positively-driven bottom roll of less velocity, said belt being adapted to move in the same direction with the roving for positively feeding the roving to a forward pair of top and bottom draft rolls of higher velocity, the front loop of said belt being close to said last-named pair of draft rolls and capable of elongation when squeezed from opposite sides for varying the effective operating length of the upper belt-run, a cross-member to be raised and lowered engaging the outer face of the lower run of said belt, a positively-driven small roll disposed above said cross-member and coacting with the upper run of the belt, and pivotal means incorporating said cross-member and adapted to laterally guide said belt, said means being pivoted below the line of travel of the roving and intermediate the belt-driving roll and the bottom roll of the drafting stage immediately preceding the draft stage in which said belt and said cross-member operate, said means being operative upon appropriate movement to raise or to lower said cross-member and adjust it in desired elevated positions thereby positioning the cross-member and said small roll the required distance apart for forcing the belt with the necessary pressure against said small roll to squeeze together the opposite run portions of the front loop of said belt whereby said front loop will be elongated and adjusted to the desired dis-

tance toward the nip of the draft rolls receiving the roving from said belt.

18. In a guiding device for an endless belt of a textile drawing mechanism having a positively-driven lower roll provided with a reduced neck portion connecting two enlarged portions that grip and move a belt, the arrangement of swingable side plates which are mounted adjacent the ends of said enlarged portions of the lower roll member for laterally guiding a belt on each of said enlarged portions, and the employment of cross-members rigidly connecting the two side

plates associated with each enlarged portion in which each cross-member is arranged at the forward part of these plates for engaging the outer face of the lower run of an endless belt to form a support over which slides the front loop of the belt, and means engaging said side plates at their rearward parts for swinging said plates to vary the position of said cross-member which supports said front loop of the belt, thereby to vary said front loop.
